ABSTRACT OF THE DISCLOSURE

A gas liquefier having a coiled capillary tube positioned within a cavity of a dewar. Insulation material is positioned on the exterior of the coil to form a seal between the coil and the dewar. The apparatus employs the "Joule-Thomson" effect.

This invention relates to gas liquefiers in which so-called "permanent" gas at high pressure is expanded to substantially atmospheric pressure in an expansion nozzle or orifice after passing through a heat exchange coil, the expanded gas flowing back over the coil in countercurrent with the incoming high pressure stream. These liquefiers will be referred to as liquefiers of the type described. Joule-Thomson expansion at the orifice produces cooling which, due to the heat exchanger, proceeds progressively until a sufficient depth of temperature is reached to cause liquefaction of a portion of the gas issuing from the orifice. The so-called permanent gases which can be liquefied in this manner include air, oxygen, nitrogen, argon, krypton, and xenon.

Hydrogen can also be liquefied in this manner but the compressed stream of hydrogen must be pre-cooled with a liquefied gas such as nitrogen before it is fed into the heat exchanger.

The heat exchanger in such liquefiers may take the form of a coil, a coiled helix or a series of coils or coiled helices wound round a mandrel which is inserted in a vacuum insulated cylindrical flask or dewar. The inner wall of the dewar "in combination with the mandrel" serves to provide an annular passage for the return gas, causing it to traverse the coil.

Such liquefiers are primarily designed to meet sporadic demands for the production of small quantities of liquefied gas from high pressure gas stored in a cylinder. A typical instance of such a demand is for demonstration purposes in educational establishments. In such cases the dewar is made of transparent material such as glass so that the formation of liquid can be easily seen. Another example is the cooling of an instrument, such as an infra red detector, which can conveniently be housed in the transparent vessel. Other sporadic demands for small quantities of liquefied gas arise in cryosurgery and in the low temperature preservation of biological tissue, such as corneal graft material.

Where the demand for small quantities of liquefied gas is sporadic, storage of the gas in the liquid state is uneconomical due to evaporation losses. The provision of a compressor to provide a source of high pressure gas, such as air, for liquefaction entails substantial capital outlay not only in respect of the compressor but also for the purification train which is essential to prevent solid particles of high melting point constituents, such as water and carbon dioxide, from blocking the heat exchanger passages.

Gas to be liquefied in liquefiers of the type described is, therefore, generally obtained from storage vessels or cylinders containing the gas at pressures of 2,000 p.s.i. and higher. The process of liquefaction cannot be sustained

2

once the pressure has fallen below about 800 p.s.i. and hitherto with liquefiers of known type, it has not been possible to achieve liquefaction from a warm start up if the initial pressure in the cylinder is much below 2,000 p.s.i.

It is an object of this invention to provide a liquefier of the type described in which the onset of liquefaction from a warm start up is achieved with lower gas consumption than heretofore.

10 Another object of this invention is to provide a liquefier by means of which a liquefied fraction can be obtained from a warm start up using a source of pressure lower than 2,000 p.s.i.

According to this invention there is provided a gas liquefier of the type described comprising a substantially cylindrical heat insulated vessel, a substantially cylindrical heat exchanger formed from capillary tubing, and fitting into said vessel, said heat exchanger having an expansion orifice at one end, an inlet header connected to the other end of said heat exchanger for coupling the heat exchanger to a source of compressed gas, a sheath of heat insulating material fitting round the heat exchanger to inhibit thermal interchange between the heat exchanger and the vessel, and sealing means to secure the heat exchanger 15 in the vessel and to direct the return flow of expanded gas inside the sheath in thermal contact with the capillary tubing.

The sealing means may conveniently be an integral part of the sheath.

30 The sheath is preferably wrapped tape of low heat capacity insulating material such as Terylene, fibre glass or aluminised Terylene.

The sealing means in such case can be formed from additional winding of tape about the inlet end of the 35 heat exchanger to provide a seal at the mouth of the vessel.

The gas liquefier may be adapted to be fitted within a back-flush unit for the clearance of any blockage occurring in the capillary tubing.

40 An embodiment of the invention is shown by way of example in the accompanying drawing which is a view in longitudinal section of a gas liquefier fitted into a dewar flask.

Referring to the drawing the liquefier comprises a double heat exchange coil 10 of coiled capillary tubing 11 wound around a mandrel 12. The mandrel 12 is a thin walled stainless steel tube three inches long, one end of which is soldered onto a central boss of a header 13. The mandrel tube is closed at its other end by a plug 50 14.

45 The double coil 10 is formed from a single 10 ft. length of capillary tubing 11 of 0.3 mm. inside diameter. This is first coiled into a helix leaving its ends uncoiled, and is then straightened in the region of its centre 55 and bent into a U shape, the two arms of which are coiled around the mandrel 12 as a double helix. The uncoiled ends of the capillary tube extend into the header 13 and are sealed thereto by soft solder, and within the header the open ends of the tube are bent over as indicated 60 to minimize entry into the tubes of solid particles entrained in the gas stream. The header 13 is internally screwthreaded for the reception of an adaptor 16 having a nipple 17 for connection to a high pressure gas source such as a pressurized cylinder. The chamber within the 65 header is sealed by a resilient washer 18.

The central portion 15 of the tubing 11, which is located at the base of the U shape formed as described, is located in a small slot in the plug 14. In this region an orifice of about 0.003 inch diameter is drilled in the 70 capillary tube wall, this providing an outlet orifice for pressurized gas supplied to the tube ends via the header 13.

After the coil 10 has been formed, Terylene cord 20 is wrapped around the coil outside to fill in the surface indentations and to give a relatively smooth cylindrical surface. Terylene tape is then tightly wound around the outside of the whole coil, so as to form an insulating sheath 21. An additional winding of tape 22 is provided around the inlet end of the coil so as to provide a plug which is a push fit into the dewar vessel 23. This plug provides sealing means which prevent return gas flow outside the sheath 21, so ensuring that all expanded gas passes over the coil. Apart from directing the return gas in this way, the sheath reduces inflow of heat from the relatively warm inner wall of the dewar vessel, and substantially improves performance of the liquefier on warm start-up. It has been found that, in producing liquid air from compressed air at 2,000 p.s.i. the provision of the insulating sheath 21 reduces the time taken from warm start-up to liquid production from 4½ minutes to just over one minute. Furthermore, the minimum pressure needed to produce liquid with a warm start-up is reduced from 1,800 p.s.i. to 1,500 p.s.i. by provision of the sheath.

With the liquefier described, at least three liquefactions from warm start-up can be demonstrated using the four litre cylinder containing dry air at 2,350 p.s.i. and producing liquid for two minutes in each case. While warm start-up cannot be used with a starting pressure of less than 1,500 p.s.i. if the liquefier is operated continuously it can operate until the pressure drops to 800 p.s.i. or for about 20 minutes starting at 2,350 p.s.i.

What is claimed is:

1. A gas liquefier of the type described comprising a substantially cylindrical heat insulated vessel, a substantially cylindrical heat exchanger formed from capillary tubing, and fitting into said vessel, said heat exchanger having an expansion orifice at one end, an inlet header connected to the other end of said heat exchanger for coupling the heat exchanger to a source of compressed gas, a sheath of heat insulating material fitting round the heat exchanger to inhibit thermal interchange between the heat exchanger and the vessel, and sealing means to secure the heat exchanger in the vessel and to direct the return flow of expanded gas inside the sheath in thermal contact with the capillary tubing.

2. A gas liquefier of the type described comprising a substantially cylindrical heat insulated vessel, a substantially cylindrical heat exchanger formed from capillary tubing, and fitting into said vessel, said heat exchanger having an expansion orifice at one end, an inlet header connected to the other end of said heat exchanger for coupling the heat exchanger to a source of compressed gas, a sheath of

heat insulating material fitting round the heat exchanger to inhibit thermal interchange between the heat exchanger and the vessel, and sealing means which is an integral part of said sheath to secure the heat exchanger in the vessel and to direct the return flow of expanded gas inside the sheath in thermal contact with the capillary tubing.

3. A gas liquefier of the type described comprising a substantially cylindrical heat insulated vessel, a substantially cylindrical heat exchanger formed from capillary tubing, and fitting into said vessel, said heat exchanger having an expansion orifice at one end, an inlet header connected to the other end of said heat exchanger for coupling the heat exchanger to a source of compressed gas, a sheath consisting of wrapped tape of low heat capacity insulating material fitting round the heat exchanger to inhibit thermal interchange between the heat exchanger and the vessel, and sealing means to secure the heat exchanger in the vessel and to direct the return flow of expanded gas inside the sheath in thermal contact with the capillary tubing.

4. A gas liquefier of the type described comprising a substantially cylindrical heat insulated vessel, a substantially cylindrical heat exchanger formed from capillary tubing, and fitting into said vessel, said heat exchanger having an expansion orifice at one end, an inlet header connected to the other end of said heat exchanger for coupling the heat exchanger to a source of compressed gas, a sheath consisting of wrapped tape of low heat capacity insulating material fitting round the heat exchanger to inhibit thermal interchange between the heat exchanger and the vessel, and sealing means consisting of an additional winding of tape about said other end of the heat exchanger to secure the heat exchanger in the vessel and to direct the return flow of expanded gas inside the sheath in thermal contact with the capillary tubing.
